(57) **CLAIM**

The ornamental design for a music box, as shown and described.

DESCRIPTION

FIG. 1 is a perspective view of a music box, showing my new design;

FIG. 2 is a front elevation view thereof;

FIG. 3 is a rear elevation view thereof;

FIG. 4 is a left side elevation view thereof; and,

FIG. 5 is a right side elevation view thereof.

The broken lines in FIGS. 1-5 represent the portions of the music box that form no part of the claimed design.

1 Claim, 5 Drawing Sheets
